REMOVAL OF SPENT WOOD CHIPS FROM
EXTRACTORS USED IN ROSIN RECOVERY
PROCESSES

Gerald L. Reasor, Chicago, Ill.

No Drawing. Application February 26, 1948,
Serial No. 11,353

8 Claims. (Cl. 134—28)

1

My invention is concerned with processes relating to the treatment of wood chips in which the rosin, turpentine, pine oil and other naval stores products content thereof are recovered, and is particularly concerned with certain procedures, hereafter described in detail, for facilitating and rendering more economical such operations.

In the usual processes of treating wood chips to recover the naval stores content thereof, the chips are placed in so-called extractors, also commonly called retorts or digesters. These extractors, which may vary in size, are usually of cylindrical shape and may, for example, have a height of 16 to 20 feet and a diameter of 7 to 9 feet and may hold from 8 to 10 tons of wood chips. The chips may be supported on a perforated plate mounted in the lower part of the extractor. The extractor is provided with a large door adjacent the lower part thereof. The wood chips, which may be made by cutting and shredding the wood and stumps from the pine trees, are loaded into the extractor through an opening in the top which is adapted to be closed by a suitable door or closure. A bed of substantial height is built up, usually to near the top of the extractor. Thereupon, live steam is frequently passed through the bed of chips to drive off a substantial part of the turpentine and pine oil. The thus treated wood chips are then subjected to extraction with an organic solvent, for example, gasoline or other low boiling or volatile petroleum hydrocarbon solvents, at elevated temperature, which dissolves out of the wood chips the rosin, residual turpentine, pine oil and other solvent-soluble ingredients. In usual commercial practice, a series of extractors, say five or six, is subjected, by the multiple extraction process, to the action of the solvent, the chips in each extractor of the series being washed with several batches of solvent in succession, and each batch of solvent is used to wash the chips in the several extractors in the series. After the final washing of the chips in an extractor, that extractor is cut out of the system, the solvent is drained off, and the chips are usually subjected to the action of steam to remove the adhering solvent.

When all, or as much as is commercially feasible, of the desired solvent-soluble materials are removed from the wood chips, the resulting residue or spent chips must be removed from the extractor so that the latter may be recharged with a load of fresh wood chips for subsequent extraction therefrom of rosin and the like. As a result of the extraction treatment, the bed of

2

spent chips forms a relatively matted body which is difficult to remove from the extractors. Removal is conventionally accomplished by opening the door adjacent the bottom of the extractor and the usual top closure and hacking away at the residues by means of forks, picks, rods and the like in order to break up the matted mass. In the usual case, this requires the services of two or more men and the work is difficult and must be accomplished under trying conditions due to the fact that the spent chips are still hot and steaming when the extractor is opened for discharging the spent chips.

Numerous attempts have been made in an effort to facilitate the removal of the spent chips. Thus, for example, the utilization of a screw mechanism to loosen and remove the spent chips has been suggested. Efforts have also been made to blow out the spent chips, either through the top or the bottom of the extractor by means of steam or a gas under considerable positive pressure. None of these procedures has, to my knowledge, proven to be feasible; and the use of manual labor, difficult and uneconomical though it is, has continued in the main to constitute the practice in commercial operations.

In accordance with my invention, the removal from the extractors of the spent chips or residue, resulting from the solvent extraction of rosin and the like from wood chips, may be materially facilitated in a relatively simple and efficacious manner. I have found, in general, that if the spent chips are subjected to the action of a hot, dilute acid solution, particularly at elevated temperatures and pressures, the matted character of said spent chips is modified so that, when the solution is removed, the solid residue may readily be removed either by blowing with steam under pressure or by any other means.

In the preferred manner of practicing my invention, the extractor containing the spent chips is closed and steam is admitted thereto until a pressure of several atmospheres, for example, about 40 to about 60 pounds per square inch, is built up in the extractor. A dilute acid solution, which is preferably one containing about 0.5% to 2.0% sulfuric acid, preferably at an elevated temperature, for example, at about 150-190 degrees C., is admitted under pressure into the extractor at the top through a suitable inlet pipe at a controlled rate and allowed to pass through the chips. A suitable rate of introduction of the dilute acid solution is about 600-800 pounds per minute where the extractor contains 8 tons of chips. When the solution begins to permeate

the bed of chips and trickle from the bottom, a valve in the bottom of the extractor is opened and thereafter the solution is allowed to drain therefrom continuously until the process is completed. This usually requires from about one to several hours. As a result of such treatment, the matted character of the chips is modified so that, when the solution is drawn off, the solid residue may readily be removed from the extractor. This may be done with shovels or the like but is most conveniently accomplished by closing off the extractor, opening an auxiliary valve to a discharge pipe preferably located near the bottom of the extractor, and then admitting a gas, particularly steam, under positive pressure, into the extractor to blow out the residue. This operation takes only a very short time and is accomplished with a minimum of manual labor.

While I prefer to subject the spent chips to the initial action of steam before the introduction of the dilute acid solution, it is not necessary that this be done since, in the usual case, the spent chips will be at a somewhat elevated temperature as a result of the treatment thereof for extraction of the rosin, turpentine, pine oil, etc. therefrom.

While I find sulfuric acid to be most satisfactory because of its low cost and ready availability, I may use dilute solutions of other acids as, for example, hydrochloric acid, sulfurous acid, acetic acid, and the like acids of organic or inorganic character. In the case of sulfuric acid, a dilution of the order of 0.5% to about 2.0% is quite satisfactory although, of course, the degree of dilution may vary. In the case of other acids, the concentration thereof will vary depending upon the strength thereof but, in all cases, the solutions are dilute in character. The temperature of the acid solution is preferably elevated and it is particularly preferred that it be in excess of 100 degrees C., most desirably within the range of about 150 to 200 degrees C. It will, of course, be understood that the extractor and its associated parts should be made of or lined with material which will withstand the corrosive action of the acid solutions under the particular conditions under which they are employed. The acid solutions which are drained out of or otherwise removed from the extractors as a result of the treatment of the spent wood chips may, if desired, be treated to recover the valuables contained therein.

While I have described my invention in detail, no unnecessary limitations shall be read thereunto, the scope of said invention being set out in the claims.

What I claim as new and desire to protect by Letters Patent of the United States is:

1. The method of removing a matted bed of substantial thickness of spent wood chips from an extractor after the extraction of rosin from said chips by a solvent extraction procedure which comprises forcing a hot, dilute acid solution through said bed of spent wood chips until the matted character of said chips is modified, and, after drawing off said solution, removing the solid residue from said extractor.

2. The method of removing a matted bed of substantial thickness of spent wood chips from an extractor after the extraction of rosin from said chips by a solvent extraction procedure which comprises forcing a hot, dilute sulfuric acid solution through said bed of spent wood chips until the matted character of said chips is

modified, and, after drawing off said solution, blowing the solid residue from said extractor.

3. The method of removing a matted bed of substantial thickness of spent wood chips from an extractor after the extraction of rosin from said chips by a solvent extraction procedure which comprises forcing a hot, dilute acid solution, under a pressure in excess of atmospheric pressure, through said bed of spent wood chips until the matted character of said chips is modified, and, after drawing off said solution, subsequently removing the solid residue from said extractor.

4. The method of removing a matted bed of substantial thickness of spent wood chips from an extractor after the extraction of rosin from said chips by a solvent extraction procedure which comprises subjecting said spent chips to the action of steam, then forcing a dilute acid solution, under a pressure in excess of atmospheric pressure, through said bed of spent wood chips until the matted character of said chips is modified, and, after drawing off said solution, removing the solid residue from said extractor.

5. The method of removing a matted bed of substantial thickness of spent wood chips from an extractor after the extraction of rosin from said chips by means of a volatile petroleum hydrocarbon solvent which comprises subjecting said spent chips to the action of steam under pressure, forcing a dilute sulfuric acid solution, under a positive pressure, through said bed of spent wood chips until the matted character of said chips is modified, and, after drawing off said solution, subsequently removing the solid residue from said extractor.

6. In a method wherein a body of substantial depth of wood chips is placed in an extractor chamber having a height and a diameter of at least several feet and is treated with a solvent to remove rosin from said chips leaving a relatively matted residue of hot, spent chips in said extractor which is difficult to remove therefrom, the steps of removing said chips which comprise forcing a dilute acid solution, at elevated temperature and pressure, through said bed of chips until the matted character of said chips is modified, and, after drawing off said solution, removing the solid residue from said extractor.

7. In a method wherein a body of substantial depth of wood chips is placed in an extractor chamber having a height and a diameter of at least several feet and is treated with a volatile organic solvent to remove rosin from said chips leaving a relatively matted residue of hot, spent

chips in said extractor which is difficult to remove therefrom, the steps of removing said chips which comprise forcing a dilute sulfuric acid solution of about 0.5% to about 2.0% concentration, at a temperature exceeding 100 degrees C. and under a pressure of several atmospheres, through said bed of chips until the matted character of said chips is modified, and then, after drawing off said solution, blowing the solid residue from said extractor.

8. In a method wherein a body of substantial depth of wood chips is placed in an extractor chamber having a height and a diameter of at least several feet and is treated with a volatile hydrocarbon solvent to remove rosin from said chips leaving a relatively matted residue of hot, spent chips in said extractor which is difficult to remove therefrom, the steps of removing said chips which comprise subjecting said spent chips to the action of steam under positive pressure,

forcing a dilute sulfuric acid solution of about 0.5% to about 2.0% concentration, at a temperature between about 150 and 200 degrees C. and under a pressure of several atmospheres, through said bed of chips until the matted character of said chips is modified, and, after drawing off said solution, blowing the solid residue from said extractor by means of steam under substantial positive pressure.
